(57) **CLAIM**

I claim the ornamental design for a disposable brew basket for electric coffee maker, as shown and described.

DESCRIPTION

FIG. 1 is a perspective view, as seen from the top, front, left side of a disposable brew basket that is formed in accordance with an exemplary embodiment of the present invention; FIG. 2 is a front elevational view of the brew basket of FIG. 1;

FIG. 3 is a rear elevational view of the brew basket of FIG. 1;

FIG. 4 is a left side elevational view of the brew basket of FIG. 1;

FIG. 5 is a top plan view of the brew basket of FIG. 1; and, FIG. 6 is a bottom plan view of the brew basket of FIG. 1.
